UNITED STATES PATENT OFFICE

109,436

DESIGN FOR A BEDSPREAD

Harriette A. Lawson, Signal Mountain, Tenn.

Application April 5, 1938, Serial No. 76,299

Term of patent 3½ years

To all whom it may concern:

Be it known that I, Harriette A. Lawson, a citizen of the United States of America, residing in Signal Mountain, Chattanooga, county of Hamilton, and State of Tennessee, have invented a new, original, and ornamental Design for a Bedspread, of which the following is a specification, reference being had to the accompanying drawing, forming part thereof, wherein,

The figure is a plan view of a complete bedspread showing my new design.

I claim:

The ornamental design for a bedspread, substantially as shown.

HARRIETTE A. LAWSON.
